[57] CLAIM

The ornamental design for an electric light bulb, as
shown and described.

DESCRIPTION

FIG. 1 is an orthogonal view of the invention;
FIG. 2 is a front view of the invention on a reduced
scale;
FIG. 3 is a left view of the invention on a reduced scale;
FIG. 4 is a top view of the invention on a reduced scale;
and,
FIG. 5 is a bottom view of the invention on a reduced
scale.FIG. 1

FIG. 2

FIG. 3

FIG. 4

FIG. 5
